UNITED STATES PATENT OFFICE.

JOHANNES TH. SENTROP, JR., OF MONTREAL, QUEBEC, CANADA.

CONSTRUCTION OF FLOORING OR THE LIKE.

1,410,768.

Specification of Letters Patent. Patented Mar. 28, 1922.

Application filed June 22, 1918. Serial No. 241,423.

To all whom it may concern:

Be it known that I, JOHANNES THEODORES SENTROP, Junior, a subject of the Queen of Holland, and resident of the city of Montreal, Province of Quebec, Canada, have invented certain new and useful Improvements in the Construction of Flooring or the like, of which the following is a specification.

10 This invention is particularly adapted for the construction of floorings or the like, of reinforced concrete, and its object, with the most practical economy in material, is to provide a solid and light flooring of a plurality of sections easily and quickly put together without the necessity of using temporary scaffolding, and without sacrificing either tensional or compressive strength.

Another object is to so anchor the sections 20 together and to the walls and main beams of the building that with these and the addition of sufficient material to act as fillers and binders a complete monolithic structure will be obtained.

25 According to my invention I first make up elongated beams of a particular shape and embodying the desired metal reinforcements, and where conditions require it, form the ends of the beams to present anchoring elements. The floor space is then completely 30 filled up by the requisite number of beams, strengthening and anchoring mediums being introduced at the points where such are needed.

35 The beams, the manner in which same are formed and the method of constructing the flooring as well as further objects and advantages of my invention will be hereinafter more fully described.

40 For full comprehension, however, of my invention, reference must be had to the accompanying drawings forming a part of this specification in which like symbols indicate the same parts and wherein.

45 Figure 1 is a longitudinal sectional view of a portion of a building showing my improved flooring;

Fig. 2 shows the ends of the beams linked together;

50 Fig. 3 is a transverse sectional view on line 2—2 Fig. 1;

Fig. 4 is a perspective view of my improved beam;

55 Fig. 5 is a perspective view of a form of beam end;

Figs. 6 and 7 are similar views of modified forms of beams ends;

Fig. 8 illustrates the various steps during the formation of the beam;

Figs. 9 and 10 modifications, in cross section of the beam;

Fig. 11 illustrates the beam supported by iron girders, and

Fig. 12 is a perspective view of a portion of the bottom of the flooring with ceiling applied.

In the drawings, 2 indicates the top of my improved beam, 3 the side webs, the outer sides of the latter being usually made inclined towards the bottom so that the outside of the beam is practically of keystone shape in cross section, while the inner sides of the webs 3, are disposed at right angles to the roof of the beam interior and if desired, the junction of the roof and webs 70 may be rounded making such interior of substantially inverted channel shape in cross section. Both the inner and outer lower portions of the webs may be flared as at 4, and each end of the beam channel closed 80 by a transverse wall 5 formed in one with the top and side webs, such walls presenting outer faces 6, inclining outwardly towards the bottom, the lower portions presenting supporting faces for the beam. 85

In order that the beams will be enabled to anchor one with the other and to the building walls, I provide the ends thereof with anchoring elements of which three forms are shown in the drawings. Fig. 5 90

illustrates the manner in which the beam end is formed when such end is to be anchored to other beam ends, this formation presenting a recess 8 formed by extending the side webs 3 a short distance beyond the 95 walls 5, the inner sides of the recess having curved surfaces 9 terminating with the face of the transverse wall 5. The formation illustrated in Figure 6 differs from that just described in that the base of the walls 5, are 100 extended, as at 10, to coincide with the webs 3, to form a pocket indicated at 11, and this formation is used in cases where the end of the beam is to anchor into the outside supporting wall of the building. To support 105 the ends of the beams suitable bases, indicated at 12, may be formed in the building walls. Of course if the flooring to be built is not too large to be spanned by one beam length both ends of the latter will be formed 110

alike. On the other hand when more than one beam is required to span the space only that end of the beam to anchor into the wall of the building will be so formed, the other 5 end of the beam being formed according to the end illustrated in Fig. 6.

The modified form of beam end illustrated in Fig. 7 is used when it is desired to add 10 strength to the floor to take up exceptional stress, this form of end differing from that illustrated in Fig. 6 in that the pocket 13 is inverted by extending the beam top 2 to coincide with the extended ends of the webs 3, and omitting the extension 10 of the trans- 15 verse wall base.

If a very cheap structure is desired and one not likely to be subjected to heavy loads, the anchoring members and end walls may be omitted and the beams formed of inverted channel shape in cross section shown 20 in Fig. 4, with the inner and outer sides of the top, and webs parallel with each other, and this form, with the addition of the end walls serving as bases, can be used to advantage 25 for floorings in buildings in which steel I beams are utilized as main bearers. An example of one use is shown in Fig. 11 in which the beam end walls rest upon the projecting flange of the I-beam, the space between 30 the end walls and the I-beam channel being filled in with concrete or cement mortar or the like.

The reinforcements I prefer to use consist of longitudinal side rods or bars 14 bent 35 back upon themselves with their ends bound together as at 15. These side rods are embedded in each of the lower parts as well as in both sides of the upper of the webs, lengthwise thereof and are secured together 40 by a series of transverse stirrups 16 fastened to the rods in any preferred manner and spaced diminishingly from the centre towards the ends of the rods, such rods with the stirrups presenting a skeleton frame of 45 substantially inverted U-shape in cross section. The lower portion of any desired number of the stirrups are provided with fastening clips 17 extending downwardly, the purpose of which will be hereinafter explained.

A typical method of forming the beams is illustrated in Fig. 8 which shows the successive steps followed. A platform of suitable material such as wet sand, indicated at 55 18, is provided on which the outer sides of the mold frame 19 are laid, after which concrete sufficient to form a first layer or base 20 is poured in. The skeleton reinforcements indicated at 21 are then pressed into 60 the layer of concrete, the webs being uppermost. A second layer of concrete 22, is poured in to cover the top of the reinforcements and form the roof of the inverted channel, after which the mold frame boards

23, to form the channel webs and those for 65 the beam ends (not shown) are placed in position and additional concrete poured in to completely envelop the skeleton reinforcements. It will be noted that the mold boards for the sides of the beam, both inner and 70 outer, are longitudinally outwardly curved as at 24, the curvatures being provided to give the flares to the sides of the beam webs. Before the concrete has fully set transverse 75 openings 25, the purpose of which will be hereinafter explained, are formed through the extended portions of the webs 3, at such points that the openings in the webs of all beams will register; and at the same time should accommodation be needed for water 80 pipes or the like such may be provided for by forming openings at suitable points in the beam.

Figure 2 illustrates the manner in which the flooring is laid to cover a space too large 85 to be spanned by a single beam length. The beams are laid side by side in lines with the end formed according to Fig. 6 resting and anchoring into the building walls and the inner ends, formed according to Figure 5, 90 rest on the customary intermediate walls or main beams 26. The beams in one line are laid in staggered relation to those in the other line with the projecting webs of one line engaging with or fitting within those 95 of the other line.

In order to prevent lengthwise displacement of the beams and for strengthening purposes, metal rods or bars 27 extending the 100 full width of the flooring are inserted in the transverse openings 25 in the web ends, such rods being fastened in any preferred manner to the reinforcing rods 2 of the webs. Wedge shaped strips of wood, or other suitable material, indicated at 28, are laid lengthwise 105 between the beams and carried by the outer flared edges of the latter and serve as a base for the concrete or cement mortar filling between the beams as well as a medium from which wire or other material to 110 form a ceiling may be stretched and the clips 17 serve to connect the ceiling and the reinforcement formed thereby to the reinforcement within the beam. Spaces are left below the wedge strips 28 to accommodate 115 concrete or mortar cement filling, which keys the ceiling to the flooring base.

The longitudinal spaces between the beams, the spaces between the ends of the beams and within the recesses and between 120 the beam and side walls and main beams of the building are then filled in with concrete or cement mortar this having the effect of anchoring the beams together and to the walls of the building and forming a complete monolithic structure. To provide additional strength at the points of greatest stress, usually the ends of the beams, any

suitable quantity of small sized metal scrap may be added to the concrete mixture at such points.

Where a ceiling is desired such may be formed of expanded metal 29 or other reinforcement stretched to the wedge strips 28, as already stated, and connected by the clips 17 to the reinforcements in the beams, the expanded metal being afterwards filled in 10 with cement or other mortar and finished off in any desired way. The addition of a ceiling connected to the bottom of the flooring as just described has the advantage by its connection to and close co-operation with 15 the reinforcement within the beams, of imparting additional strength to the flooring.

The flares on the lower inside parts of the webs may serve to accommodate bases, such as metal plates, wooden blocks or the like 20 which can be wedged in and from which shafting, belting or the like may be hung.

From the foregoing it will be apparent that the beams, which may be of any desired dimensions and reinforcements, may 25 be made wherever may be most convenient to the work or building either in the shop or adjacent the building being constructed.

While I have illustrated and described the interior of the beam as of inverted channel 30 shape in cross section and the exterior of key-stone shape in cross section, it is obvious that variations of this formation may be made with advantage and without departing from the spirit of my invention. 35 For instance, when an exceptionally heavy load is to be carried or an economy of vertical space is desired, the beam interior could be made of arch-form in cross section as shown in Fig. 9, or the points of junction of 40 the inner sides of the webs and the top could be curved as shown in Fig. 10.

What I claim is as follows:—

1. In a monolithic structure comprising a plurality of reinforced concrete beams of 45 channel form in cross-section said beams each including a top portion and side webs, the upper portions of the outer surfaces of the webs inclining inwardly and downwardly from said top portion and the lower portions of such outer surfaces inclining outwardly and downwardly with respect to said inwardly inclined portions such inclinations forming a continuous unbroken line to the beam base, the oppositely inclined portions of the outer surface of each web being of substantially the same pitch as the webs of the opposing beams and forming an obtuse angle between them.

2. A reinforced concrete beam of channel 60 form in cross-section, including a top portion and side webs the inner lower portions of which latter are flared towards each other to form supporting shelves and the outer surfaces of which incline inwardly from said 65 top portion and flare outwardly to form sup-

porting shelves at their longitudinally extending edges which are remote from the top portion.

3. A reinforced concrete beam of channel form in cross-section, including a top portion, side webs, the inner lower portions of which latter are flared and the outer surfaces of which incline inwardly from said top portion and flare outwardly, to form supporting shelves, at their longitudinally extending edges which are remote from the top portion, and a wall extending transversely between the side webs near the end of the channel beam, the outer surface of such transversely extending wall being outwardly inclined from said top portion.

4. A reinforced concrete beam of channel form in cross-section, including a top portion, side webs, the inner lower portions of which latter are flared and the outer surfaces of which incline inwardly from said top portion and flare outwardly, to form supporting shelves at their longitudinally extending edges which are remote from the top portion, and a wall extending transversely between the side webs near the end of the channel beam, the inner surface of said transverse wall being substantially perpendicular to the top portion and the outer surface of the transverse wall being outwardly inclined with respect to the top portion.

5. A reinforced concrete beam of channel form in cross-section, including a top portion, side webs and an end wall, portions of the said webs extending beyond the outer side of the end wall and forming with the latter a recess at the end of the beam, the outer surfaces of the side webs being inwardly inclined from the top portion and the longitudinally extending edges of the side webs which are remote from the top portion, being outwardly flared to form supporting shelves.

6. A reinforced concrete beam of channel form in cross-section, including a top portion, side webs and an end wall, portions of the side webs extending beyond the outer side of the end wall and forming a recess therewith at the end of the beam, the opposing inner surfaces of the extensions of the side webs being curved in the longitudinal plane of the beam, the curvature being concave at the juncture points of the web extensions and end wall and convex towards the outer ends of the extensions.

7. A reinforced concrete beam of channel form in cross-section, including a top portion, side webs, the inner lower portions of which latter are flared and the outer surfaces of which incline inwardly from said top portion and flare outwardly to form supporting shelves at their longitudinally extending edges which are remote from the top portion, an end wall, portions of the side webs extending beyond the outer side of the

end wall, an extension of the end wall extending in the longitudinal plane of the beam from one edge of the end wall to and connecting the extensions of the side webs, 5 the end wall and side web and end wall extensions forming a recess at the end of the beam and the opposing inner surfaces of the extensions of the side webs being curved in the longitudinal plane of the beam, the 10 curvature being concave at the juncture points of the side web extensions and end wall and convex towards the outer ends of the extensions.

8. An elongated reinforced concrete beam, 15 the interior of which is of inverted channel shape in cross section, and comprising a top, side webs the outer sides of which are inwardly inclined downwardly, a transverse wall at each end closing the channel, the 20 outer faces of such end walls being downwardly outwardly inclined and each end of the beam being provided with anchoring members projecting beyond the transverse walls and formed of extended portions of 25 the beam.

9. An elongated reinforced concrete beam

the interior of which is of inverted channel shape in cross-section, and comprising a top, side webs the outer sides of which are inwardly inclined downwardly and both the 30 inner and outer lower portions are outwardly flared, a transverse wall at each end closing the channel, such end walls being downwardly outwardly inclined, and each end of the beam being provided with anchoring members projecting beyond the transverse walls and formed of extended portions 35 of the beam.

10. An elongated reinforced concrete beam of inverted channel shape in cross-section, 40 comprising a top, side webs and end walls, portions of the side webs extending beyond the end walls, such end walls with the extended ends of the webs forming a recess at each end of the beam, the outer sides of the 45 webs being inwardly inclined downwardly and both the inner and outer lower edges of the webs being outwardly flared.

In testimony whereof, I have signed my name to this specification.

JOHANNES TH. SENTROP, JR.
